CLAIM

The ornamental design for a clamping and cutting tool for tubes, as shown and described.

DESCRIPTION

FIG. 1 is a front elevational view thereof;
FIG. 2 is a rear elevational view thereof;
FIG. 3 is a top plan view thereof;
FIG. 4 is a bottom plan view thereof;
FIG. 5 is a left side elevational view thereof;
FIG. 6 is a right side elevational view thereof; and,
FIG. 7 is a perspective view of a clamping and cutting tool for tubes showing my new design.
